UNITED STATES PATENT OFFICE.

JOSEPH HOFFAY, OF NEW YORK, N. Y.

PHONOGRAPH REPRODUCER.

Application filed May 7, 1920. Serial No. 379,449.

To all whom it may concern:

Be it known that I, JOSEPH HOFFAY, a citizen of Mexico, residing at New York, in the county of New York and State of New

5 York, have invented certain new and useful Improvements in Phonograph Reproducers, of which the following is a clear, full, and exact description.

This invention relates to sound boxes, 10 phonographs, gramophones and the like, and more particularly to the means for mounting the stylus lever or carrier on the sound box, whereby the desired degree of tension on the diaphragm may be had with the 15 greatest convenience in manipulation.

The present invention is in the nature of improvement on devices disclosed in prior patents, as follows: 1,326,932, Jan. 6, 1920; 20 1,291,887, Jan. 21, 1919, and in my prior application Serial No. 242,988 filed July 2, 1918.

In the present invention, I have preserved the free mounting of the stylus carrier disclosed in my prior cases and hold it to its 25 bearing by resilient means. In the present invention I also apply yielding forces to the diaphragm, said forces acting in opposite directions so that the diaphragm is quickly responsive to vibrations and also 30 quickly returns to its normal state when displaced therefrom. These yielding forces also hold the stylus carrier to its fulcrum.

An important feature of my present invention resides in the provision of means 35 whereby these yielding forces may be readily adjusted, and preferably this adjustment is accomplished by providing spring arms extending from the fulcrum in opposite directions but having their major portion lying 40 in a plane substantially parallel to the plane of the diaphragm, and having means engaging their free ends for longitudinal adjustment to said spring arms to thereby vary the pressure both against the diaphragm 45 and against the fulcrum of the stylus carrier.

Other features and advantages will be apparent from the following detailed description and claims when taken in connection 50 with the accompanying drawing, in which

Fig. 1 is a front elevational view of my improved sound box;

Fig. 2 is an end elevation of the same;

Fig. 3 is a bottom view partly in section 55 along the line 3—3, Fig. 1;

Fig. 4 is a bottom elevational view;

Fig. 5 is a section through the stylus carrier and showing particularly the knife edge for supporting the stylus carrier on the sound box;

Fig. 6 is a view similar to Fig. 3, but showing a slightly modified construction, and Figs. 7 and 8 are a detail.

Referring to the drawing, the sound box 1, which may be of any known or approved 65 construction, carries the diaphragm 2 which may be mounted therein between discs 3 of sound insulating material (see Fig. 5). Secured to the diaphragm at 4, in the customary manner, is the lever 5 forming part 70 of the stylus carrier 6, which carrier has arms 7 projecting from opposite sides thereof, said arms formed adjacent to the sound box, with knife edges engaging each a notch 8—Fig. 5—cut into the bottoms of lugs 9 75 projecting from the sound box, the notches 8 being in a plane parallel to the plane of the diaphragm.

In order that the diaphragm may quickly respond to movements transmitted to it from 80 the sound groove through the stylus carrier, said carrier is mounted so that the diaphragm is held by yielding forces which act in opposite directions. These forces are applied by spring arms 10 having their greater 85 length in a plane substantially parallel to the plane of the diaphragm, said spring arms being made of wire and are relatively long and sufficiently strong to quickly return the diaphragm to normal position. 90 Each of the arms 10 is fastened to the stylus carrier in any suitable manner, and in the particular embodiment shown the ends of the wires comprising said arms engage holes drilled into the arms 7. These wires lead 95 from the arms 7 at an angle to the plane of the diaphragm, and are again bent inwardly at 11 and again at 12. The wires are so bent that when the ends 13 are confined in any suitable manner, the wires exert a tension 100 against the stylus lever to hold it against the casing and also to exert pressure against the diaphragm.

One example of the method of binding the wires is illustrated in Fig. 8, the full lines showing the position of one of the wires after its end 13 is confined, the dotted lines showing the portion from the point 11, bent up so as to give the tension above referred to. For the purpose of varying the tension exerted by the springs 10, at 110 will, the ends 13 engage in longitudinal bores in screws 14, threaded into lugs 15, project-

ing from the sound box. Longitudinal adjustment of either screw 14 will vary the tension on its spring arm, and the tension on the stylus carrier will also be varied. The 5 pressures caused by these springs will be exerted on the diaphragm in the opposite direction, and may be very delicately adjusted.

In order that the rotational forces exerted by the spring arms 10 may be greater, I 10 have shown a form of device in Figs. 5, 6 and 7 in which there is a lateral projection 16 from each of the lugs 15, under which the end of a spring arm remote from the fulcrum of the stylus carrier extends, and 15 against which it bears. Otherwise the construction of Fig. 6 is identical with that shown in the other figures.

It is, of course, understood that variations 20 may be resorted to within the scope of the invention without departing from the spirit thereof.

What I claim as new is:

1. A phonographic sound box comprising a casing and a diaphragm in said casing, 25 a stylus carrier having an operative connection with said diaphragm and fulcrumed upon said casing, means for holding said carrier upon its fulcrum, said holding means held by said casing so that it may oscillate with said carrier, and means for varying the pressure on the diaphragm by longitudinal adjustment of said carrier-holding means.

2. A phonographic sound box comprising 30 a casing and a diaphragm in said casing, a stylus carrier having an operative connection with said diaphragm and fulcrumed upon said casing, yielding arms connected to said carrier at its fulcrum, each of said 35 arms having a portion extending from said fulcrum in opposite directions and at an angle to the plane of the diaphragm but having their greater length substantially parallel to the diaphragm, and means for 40 adjustably confining the ends of said arms so that tension on said diaphragm may be varied by longitudinal movement of either 45 arm.

3. A phonographic sound box comprising 50 a casing and a diaphragm in said casing, a stylus carrier having an operative connection with said diaphragm and fulcrumed upon said casing, yielding arms connected to said carrier at its fulcrum, each 55 of said arms having a portion extending from said fulcrum in opposite directions and at an angle to the plane of the diaphragm but having their greater length substantially parallel to the diaphragm, 60 screws supported on said casing, the ends of each of said arms remote from the fulcrum engaging a longitudinal bore in a screw whereby the turning of a screw acts to vary the tension on the diaphragm.

4. A phonographic sound box comprising

ing a casing and a diaphragm in said casing, a stylus carrier having an operative connection with said diaphragm and fulcrumed upon said casing, spring arms connected to said stylus carrier at its fulcrum, each arm bent so as to provide a portion extending away from the fulcrum, a portion substantially parallel to the plane of the diaphragm, a portion extending inwardly towards the plane of the diaphragm, 70 and another portion extending substantially parallel to the diaphragm but in the opposite direction from said first-mentioned parallel portion, screws carried by said casing, said latter portion of each of 75 said arms engaging in a longitudinal bore 80 of said screw in said casing.

5. A phonographic sound box comprising a casing and a diaphragm in said casing, a stylus carrier having an operative connection with said diaphragm and fulcrumed upon said casing, spring arms connected to said stylus carrier at its fulcrum, 85 said spring arms so bent that longitudinal movement of one end of each arm will result in varying the pressure of the stylus carrier against the sound box and also the 90 rotational pressure on the stylus carrier.

6. A phonographic sound box comprising a casing and a diaphragm in said casing, a 95 stylus carrier having operative engagement with said diaphragm and fulcrumed upon said casing, spring arms connected to said stylus carrier at its fulcrum, said spring arms mounted so that one end of each 100 may be moved longitudinally, said movement resulting in varying the pressure of the stylus carrier against the sound box.

7. A phonographic sound box comprising a casing and a diaphragm therein, a stylus 105 carrier mounted on said casing on a fulcrum which is substantially parallel to the plane of the diaphragm, spring arms connected to said stylus carrier, said arms being so shaped that longitudinal adjustment thereof acts to 110 vary the pressure on said stylus carrier, and means for confining said arms near their adjustable ends.

8. A phonographic sound box comprising a casing, and a diaphragm in said casing, a 115 stylus carrier having operative connection with said diaphragm and fulcrumed upon said casing in the plane of the diaphragm, yielding arms connected to said carrier at its fulcrum, each of said arms having portions extending substantially parallel to the plane of the diaphragm but outside of said plane, and means for confining the ends of said arms remote from the fulcrum, so as to 120 produce pressure on opposite sides of said 125 diaphragm.

9. A phonographic sound box comprising a casing, and a diaphragm in said casing, a stylus carrier having operative connection with said diaphragm and fulcrumed upon 130

said casing in the plane of the diaphragm, yielding arms connected to said carrier at its fulcrum, each of said arms having portions extending substantially parallel to the plane of the diaphragm but outside of said plane, and means for confining the ends of said arms remote from the fulcrum, so as to produce tension on said stylus carrier, tending to hold it against said casing.

10. A phonographic sound box comprising a casing, and a diaphragm in said casing, a stylus carrier having operative connection with said diaphragm and fulcrumed upon said casing in the plane of the diaphragm, yielding arms connected to said carrier at its fulcrum, each of said arms having portions extending substantially parallel to the plane of the diaphragm but outside of said plane, and means for confining the ends of said arms remote from the fulcrum, so as to produce tension on said stylus carrier, tending to hold it against said casing and to rock it on its fulcrum.

11. A phonographic sound box comprising a casing and a diaphragm in said casing, a stylus carrier having operative con-

nection with said diaphragm and fulcrumed upon said casing, yielding arms connected to said carrier substantially in the plane of its fulcrum, each of said arms having portions extending substantially parallel to the plane of the diaphragm but outside of the plane of said fulcrum, and means for confining the ends of said arms remote from the fulcrum so as to produce pressure on opposite sides of said diaphragm.

12. A phonographic sound box comprising a casing and a diaphragm in said casing, a stylus carrier having operative connection with said diaphragm and fulcrumed upon said casing yielding arms connected to said carrier substantially in the plane of its fulcrum, each of said arms having portions extending substantially parallel to the plane of the diaphragm but outside of the plane of said fulcrum, so as to produce tension on said stylus carrier, tending to hold it against said casing and to rock it on its fulcrum.

Signed at New York, N. Y. this 23 day of April, 1920.

JOSEPH HOFFAY.
